US0D1106451S

(12) **United States Design Patent** (10) **Patent No.:** **US D1,106,451 S**
(45) **Date of Patent:** **** Dec. 16, 2025**

(54) **BIDIRECTIONAL BARBED SUTURE DEVICE**

(71) Applicant: **Keith Michael Nord**, Jackson, TN (US)

(72) Inventor: **Keith Michael Nord**, Jackson, TN (US)

(**) Term: **15 Years**

(21) Appl. No.: **29/939,780**

(22) Filed: **Apr. 29, 2024**

(51) **LOC (15) Cl.** **24-01**

(52) **U.S. Cl.**

USPC **D24/145**

(58) **Field of Classification Search**

USPC D24/145

CPC A61B 17/0401; A61B 17/0616

See application file for complete search history.

(57) **CLAIM**

The ornamental design for a bidirectional barbed suture device as shown and described.

DESCRIPTION

FIG. 1 is a prospective view of a bidirectional barbed suture device showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.
